UNITED STATES PATENT OFFICE.

CHARLES E. DAVIS, OF CHICAGO, ILLINOIS.

SEAL-LOCK.

SPECIFICATION forming part of Letters Patent No. 352,522, dated November 16, 1886.

Application filed March 15, 1886. Serial No. 195,350. (Model.)

To all whom it may concern:

Be it known that I, CHARLES E. DAVIS, of Chicago, in the county of Cook and State of Illinois, have invented certain new and useful Improvements in Seal-Locks, of which the following is a description, reference being had to the accompanying drawings, in which—

Figure 1 is a side view of my improved lock. Fig. 2 is a front view thereof. Fig. 3 is a front view of the same when unlocked, and Fig. 4 is an end view.

My invention relates to seal-locks designed especially to lock and seal railway freight-cars, although it may of course be used upon any other structure.

In order to protect themselves so far as possible from losses from the acts of thieves, and to facilitate the early detection of robberies when committed, the railway companies use to lock their freight-cars either a lock and a seal independent of each other or a seal-lock. In the seal-locks the seals, of whatever material composed, are arranged either so they must be destroyed before the lock can be unlocked or by the unlocking of the lock. The seals in some cases afford a little protection against the breaking into a car; but their main purpose is to discover to the employés when and where the car was entered, which is ascertained by frequent examinations of the seals. The locks now used are all forms of key-locks, of which there are no forms (except, perhaps, a very expensive form) which afford a sufficient protection against these depredations. The robberies still continue, and the railway companies suffer great loss in consequence thereof. A lock affording greater security is needed for this and other analogous uses, in combination with a seal which shall, so far as is possible, protect the lock from being unlocked, and which shall serve to detect that said lock has been opened, if such is the case.

The main object of my invention is to adapt a permutation-lock to a suitable seal, and to combine them together, so as to afford a more effective protection than any device now used to lock and seal railway freight-cars and other analogous structures.

To this end it consists, first, in the combination of a permutation-lock with an opaque

frangible seal held in position by the locking of the lock, and covering, and by its opacity concealing, the registering-points of the permutation devices; second, in the combination of a permutation-lock with an opaque frangible self-luminous seal adapted to be held in position by the locking of the lock, and covering and concealing the registering points of the permutation devices, and by its luminosity showing at night whether or not said seal remains in its position and condition as an effective protection against the unlocking of the lock; third, in the various sub-combinations herein described, and pointed out in the claims.

I am aware of the patent to Wheeler and Laffrey, No. 160,493, and I do not desire to claim as my invention anything therein shown or described. Their invention, however, is only adapted to a self-locking key-lock, which, as beforestated, affords inadequate protection.

I am the first to combine with a permutation-lock a frangible seal arranged to cover and conceal the registering devices of said lock, thereby making it necessary to break the seal to open the lock.

In the drawings which illustrate the invention, A represents a permutation-lock having a case, a^5 , in which the devices for engaging with the shackle are located, and an extension or body, a^4 , to the remote end of which the shackle is pivoted.

It is not necessary here to explain the locking mechanism further than to say that it is locked by turning the small knob or thumb-piece d , and unlocked by turning the said knob so as to bring the registering-marks on the dial D to the registering-point or mark d' upon the lock-body to a known combination, in the manner of all permutation-locks.

The dial D, which is provided with numbered lines or registering-points, is set flush with the face of the lock. A mark or registering-point, d' , is made upon the face of the lock, and the dial and mark are so arranged with reference to the other parts of the device that when the seal is in place it covers said mark and about half of the dial adjacent thereto. Upon the sides of the body a^4 of the lock I provide the flanges a^6 , having the in-

ternal grooves, $a' a'$, and at the inner ends of the grooves I prefer to place the shoulders $a^2 a^2$.

B represents the shackle or bail, which is pivoted to the ears $b b$ on the body of the lock.

5 The pivot end of said bail is made eccentric or elongated, so that when open, as shown by the dotted lines in Fig. 1, it is on a level with the face of the lock, but when closed the end b' projects outwardly beyond said face.

10 The seal C is a flat piece of some frangible material, preferably glass, and is adapted to fit into the grooves $a' a'$ and lie between the shoulders $a^2 a^2$ and the end of the lock. This seal is made opaque, either by painting it or 15 in any suitable manner. When the seal is in place, as shown in Fig. 2, it covers and conceals the lower part of the dial D and the registering-mark d' . Upon closing the shackle B and turning the thumb-piece d , thereby 20 locking the lock, the end b' of the shackle holds the seal in.

It is not designed to always place the registering-mark d' below the center of the dial; but it is the design to place said mark at different points on the lock, but always, of course, where the seal, when in place, will cover it, and by its opacity conceal its location. Thus one who knows the combination of the lock cannot open it without breaking the seal, since he 30 cannot locate the registering-points.

As a further advantage, and as a means for rendering the seal opaque, I prefer to paint said seal with some phosphorescent or self-luminous paint. The advantages of the addition of this 35 element of luminosity to the seal are numerous. For example, it enables the conductor of the train to stand by the side of the track at night as his train slowly passes and see the seals upon each car or note their absence if they are gone. 40 If the examination of the seals is to be made in the yards, it may be made without carrying a lantern, which frightens off any thieves who may at the time be at work, and thus rendering their capture very difficult.

45 As a further protection to the railway com-

panies using the above-described lock, a shipping - ticket, E, may be combined therewith. This ticket I design shall contain on one side the number of the car, date, place of shipment, &c., and on the other side words in the nature 50 of a receipt of the car and indicating the condition of the seal when received, to be signed by the party to whom the car is delivered. This ticket is placed and held beneath the seal C, as shown in Fig. 3, where it is protected from rain and dirt by the seal. To further protect the seal and the ticket and locking mechanism, I extend around the upper edge of the lock the raised flange a^3 , which sheds the rain and prevents it from getting into the lock or under the 60 seal.

Having thus described my invention, what I claim as new, and desire to secure by Letters Patent, is—

1. The combination of a permutation-lock 65 with an opaque frangible seal held securely in position by the locking of the lock, and serving to cover, and by its opacity to conceal, the registering-points of the permutation devices, substantially as and for the purpose specified. 70

2. The combination of a permutation-lock with an opaque frangible self-luminous seal held securely in place by the locking of the lock, and serving to cover, and by its opacity to conceal, the registering-points of the permutation 75 devices, and by its luminosity to show in the night-time the effective continuance of such concealment, substantially as described.

3. The combination of a permutation-lock having the dial thereof set flush with the face 80 of the lock, grooved flanges along the sides of body of the lock, and a shackle, with pivoted end made eccentric, with an opaque frangible seal, substantially as and for the purpose set forth.
